Geo. Stevens.
Attorney

UNITED STATES PATENT OFFICE

VERNON L. KEECH, OF DULUTH, MINNESOTA

RAILROAD TIE

Application filed July 13, 1931. Serial No. 550,386.

This invention relates to railroad ties, the principal object being to provide a metal tie having the characteristics of a firm and positive support for the rails of a track, together with the requisite resiliency of such a support.

Another object is to provide a tie and rail fastener therefore whereby as nearly as possible permanent attachment of the rail upon the tie is accomplished by ultimate holding adjustment of the fastener.

A further object is to produce a resilient metal tie having means associated therewith to insure same against longitudinal movement or slipping as for example around a curve in the track or the like.

Still other objects and advantages of the invention will appear in the following description thereof.

Referring now to the accompanying drawings, forming part of this application, and wherein like reference characters indicate like parts:

Figure 1 is a top plan view of one of the improved ties;

Figure 2 is a plan view of the reverse or bottom of the tie;

Figure 3 is an enlarged fragmental sectional view longitudinally the center of the tie at the point of rail mounting; and

Figure 4 is a vertical section transverse the tie as taken on the line 4—4, Figure 3.

The tie and fastener here illustrated are identical with those shown in my copending application upon an improved rail and tie fastener, filed concurrently herewith.

The tie is of sheet metal, and generally V-shaped in cross section, the upper flat surface of which is illustrated at 1 and the inclined sides at 2. The lower edges of the side portions are spaced apart throughout the full length of the tie, and directly beneath each rail engaging area of the tie these side walls are bulged outwardly in angular form as at 3, the apex of which angular bulge portion is vertical or at right angles to the flat top 1, so that a transverse section through the center of such bulged sides would illustrate a rectangularly shaped tie having no bottom whatever. These bulged portions are to pro-

vide means adequate for preventing longitudinal movement of the tie when embedded in the ground, and if so desired a third or intermediate bulged portion may be formed in the side walls of the tie as illustrated in dotted lines, Figure 2, at 4; this modification being considered no departure from the invention.

As a preferred rail fastening attachment I have illustrated the tie as having spaced rectangularly shaped holes 5, centrally of the tie, and one upon either side of the rail tread portion thereof.

Within the outermost edge of each hole, farthest from the rail tread portion, is formed an upwardly arched tongue 6 for cooperative engagement with the fastening or holding dog 7 to be installed one within each hole and ultimately brought into holding position as by swaging or pounding into place with a hammer or sledge. The dog 7 is provided with a head and tail portion, the head having a suitable mouth for grasping engagement with the edge of the base 13 of the rail, and the top portion 1 of the tie. The lips of the mouth portion are indicated at 8 and 9 and the tail at 10, so that

after the rail is in position the dog may be slipped into one of the holes 5 head first, its tail forced downwardly upon the upwardly arched free extremities of the tongue 6 sufficient to level the latter to its normal position when the corners of the tail will overlap the opposite corners of the hole 5 left as

by the tongue 6 being narrower than the hole; these corners being clearly illustrated at 11 in the two plan views of the tie as well as in Figure 3.

One materially novel feature is the resiliency or yieldability thereof in that the tie is made of a proper thickness of sheet material from which it is stamped to permit of breathing motion of the inclined sides thereof when a car wheel passes over same; this resulting of course from the free spaced edges of the inclined sides.

Having thus described my invention, what I claim and desire to secure by Letters Patent, is:

1. A railroad tie made of a single piece of sheet metal, triangular in cross section with the apex of one angle being open, and later-

ally projecting means spaced longitudinally of the tie to prevent longitudinal movement thereof.

2. As a new article of manufacture, a railroad tie made of sheet metal, substantially triangular in cross section throughout except at spaced intervals where it is substantially square in cross section.

10 3. As a new article of manufacture, a railroad tie made of sheet metal, substantially triangular in cross section throughout except at spaced intervals where it is substantially square in cross section, the lower apex and ends being open.

15 4. A stamped sheet metal railroad tie characterized by having inclined sides and open bottom to afford yieldability to the tie, and bulged portions in the sides thereof to prevent longitudinal movement.

20 In testimony whereof I affix my signature.
VERNON L. KEECH.
